LIFTING GRAB FOR INDUSTRIAL TRUCKS

Hiram J. McDonald, Jeffersonville, Ind.

Application August 5, 1947, Serial No. 766,433

4 Claims. (C.I. 214—66)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

This invention relates to loading apparatus and is particularly concerned with a mechanism for gripping an article to be lifted and transported to a point of deposit.

More specifically, it is an object of the invention to provide an attachment for industrial trucks, such as fork-lift trucks, adapted to grip articles which are to be lifted and transported from one place to another as in the handling of goods for storage, shipment, etc.

A further object of the invention resides in the provision of a gripping mechanism for industrial trucks which will operate automatically to grasp the article to be lifted thus eliminating the need of a special attendant for that purpose.

Other objects and advantages of the invention will be apparent from the following description when taken in connection with the accompanying drawings, in which,

Figure 1 is a fragmentary perspective view of the forward portion of an industrial truck with the novel attachment installed thereon and about to engage an article to be lifted;

Figure 2 is a fragmentary elevational view of the attachment in gripping position upon a box;

Figure 3 is a plane view of the apparatus; and

Figure 4 is an enlarged detailed perspective view showing the spring mounting and related parts.

In detail, the numeral 1 indicates a fork-lift truck provided with a mast 2 pivoted to the body of the truck and adapted to be tilted forwardly or backwardly as desired. Slidably mounted on the forward portion of the mast is a carriage 3 adapted to be raised and lowered for the purpose of lifting merchandise when it is to be transported and deposited in a new location.

The parts just referred to are well known in the art and form no part of the present invention except insofar as they are combined with the novel features to be described. Fixed to the carriage 3 and extending forwardly and horizontally therefrom is a boom 4 for supporting lazy tongs for gripping articles to be transported by the truck.

Swiveled to the forward end of boom 4, as by means of bolt and nut 5 is a crossbeam 6 to the ends of which the lazy tongs are pivotally connected. In the present instance, the lazy tongs comprise a set of two which are pivotally connected to the respective ends of the bar 6 and

2

have their corresponding elements rigidly connected so as to act in unison. The pivot for each of the lazy tongs in the respective ends of the bar 6 is indicated by the numeral 7 and the links for this part of the lazy tongs are indicated by the numeral 8. Pivotedly connected to the opposite ends of the links 8 as indicated by numeral 9 are the main levers 10 of the lazy tongs and, in the present illustration, grippers 11 of V-shaped cross-section are rigidly connected to the free ends of the levers 10. These grippers may be provided with linings 12 of suitable fabric such as brake lining material or the like when the apparatus is to be used for handling articles which might be damaged by the bare metal of the grippers. In the present instance, the boxes A, which are shipping crates for caskets, have their longitudinal upper edges provided with ribs B which are readily adapted to receive the channeled grippers 11. It is to be understood however that the invention is not so limited and that various other types of gripping means may be substituted for the elements 11.

In addition to the grippers 11 which connect the free ends of the levers 10, the bars 13 rigidly connect these levers so as to provide a sturdy and unitary construction. Moreover, these bars 13 are preferably provided with guide loops 14 which serve to slidably engage the free ends of a leaf spring 15 which may be secured at its mid-portion to the swivel bolt 5 and has its free ends disposed beneath the two cross bars 13 for the purpose of normally maintaining the grippers 11 in their open position.

It will be understood that the lateral pressure applied by the grippers in gripping a heavy article will be very substantial and in the case of boxes and similar articles might cause considerable damage if not modified to some extent. In the present construction therefore a bar 16 extends across the space between the grippers 11 and has its ends connected thereto by the pin and slot connections 17, thereby providing for adequate, relative movement between the grippers but limiting their inward movement so as to avoid unduly crushing the article being handled. Bars 16 of different lengths may, of course, be substituted when articles of different dimensions are to be handled.

As heretofore mentioned, it is a primary object of the invention to provide a gripping device which may be automatically operated by the operation of the lift-truck thereby avoiding the necessity of a helper or attendant for applying the gripping elements to the articles. In this

operation the mast 2 of the truck is first tilted slightly rearwardly of its normal vertical position so as to incline the boom 4 upwardly with an attendant upward inclination of the lazy tongs so that the forward gripper 11 will be in a horizontal plane somewhat above that of the rear gripper 11. The truck is then maneuvered up to the box or other article being operated upon and the carriage 3 moved vertically to bring the rear gripper into alignment with the adjacent rib B on the upper edge of the box. The truck is then moved forwardly to bring the rear gripper into gripping engagement with the rear rib B and the mast 2 is tilted forwardly to vertical position thereby bringing the forward gripper 11 into the horizontal plane of the rear gripper 11 and, of course, into the plane of the other rib B. Power may then be applied to the carriage 3 to elevate the same and in this movement the lazy tongs will operate to bring the forward gripper into tight engagement with the adjacent rib B and thereby tightly grip the box between the grippers in the usual and well known operation of tongs of this general type. Thereafter the truck may be operated to carry the article A to its point of deposit and the latter will be lowered to the floor or other place of storage and in this position the grippers 11 will automatically release the article through pressure of the spring 15 on the cross bars 13, and set the grippers in position for a succeeding operation as soon as the mast 2 is tilted rearwardly to set the rear gripper in a horizontal plane slightly below the plane of the forward gripper.

From the foregoing description taken into connection with the accompanying drawings it will be apparent to those skilled in the art that I have devised an attachment for lift-trucks which is of relatively simple construction and yet which may be operated through the maneuvering of the truck itself to cause the grippers to automatically engage and disengage an article to be handled, thereby eliminating the need for one or more workmen in otherwise attaching the article to the lifting means, and that by reason of the swivel connection between gripping device and the horizontal beam, elongated articles such as the crate A may be readily rotated through an angle of 90° or other desired angle should it be necessary to transport the article through narrow passages or doorways.

While the apparatus illustrated herein has been described in some detail, it is to be understood that various types of grippers may be substituted for the inwardly opening channel members and that various other changes may be made without in any way departing from the spirit of the invention and it is intended that all such changes be included within the scope of the appended claims.

I claim:

1. In combination with a fork-lift truck having an upright mast pivoted for swinging movement forwardly and backwardly, a carriage mounted for vertical movement on the mast, a

boom projecting from the carriage, a pair of lazy tongs arranged in parallel relation, cross-rods rigidly connecting the corresponding levers of said pair of lazy tongs, inwardly directed channel members connecting the corresponding free ends of the pair of lazy tongs, a spring for normally maintaining said tongs in open position, and means for pivotally connecting said tongs to the boom.

2. In combination with a fork-lift truck having an upright mast pivoted for swinging movement forwardly and backwardly, a carriage mounted for vertical movement on the mast, a boom projecting from the carriage, lazy tongs, means for pivoting the lazy tongs on said boom, gripping means on the free ends of the tongs, a rigid bar spanning the space between the free ends of the tongs, and a pin and slot connection between each end of the bar and the adjacent free end of the tongs.

3. In combination with a fork-lift truck having an upright mast pivoted for swinging movement forwardly and backwardly, a carriage mounted for vertical movement on the mast, a boom projecting from the carriage, lazy tongs, means for pivoting the lazy tongs on said boom, gripping means on the free ends of the tongs, and a leaf spring fixed at its mid-portion to the suspending means and having its free ends in sliding engagement with the free ends of the tongs.

4. In combination with a fork-lift truck having an upright mast pivoted for swinging movement forwardly and backwardly and a movable carriage mounted on the mast for vertical movement, a boom projecting forwardly from the carriage, a pair of interconnected grippers pivotally connected to the boom, the operative face of one gripper directed forwardly and the operative face of the other gripper directed rearwardly, whereby when the rear gripper is engaged against an article to be lifted and the carriage is raised on the mast the grippers are caused to automatically grip the article.

HIRAM J. McDONALD.
